UNITED STATES PATENT OFFICE.

HERBERT T. BALLARD, OF NORRISTOWN, PENNSYLVANIA.

DESIGN FOR A KNITTED RIB FABRIC.

Application filed December 27, 1921. Serial No. 525,267. Term of patent 7 years.

To all whom it may concern:

Be it known that I, HERBERT T. BALLARD, a subject of the King of Great Britain, residing at Norristown, county of Montgomery, State of Pennsylvania, have invented a new, original, and ornamental Design for Knitted Rib Fabrics, of which the following is a specification, reference being had to the

accompanying drawing, forming a part thereof.

The drawing is a face view of a knitted rib fabric embodying my new design.

I claim:

The ornamental design for a knitted rib fabric as shown.

HERBERT T. BALLARD.
